UNITED STATES PATENT OFFICE.

LESTER S. KUBIAC, OF YOUNGSTOWN, OHIO, ASSIGNOR TO THE PHOTOGENIC MACHINE COMPANY, OF YOUNGSTOWN, OHIO, A CORPORATION OF OHIO.

ELECTRIC-ARC LAMP.

Application filed January 3, 1927. Serial No. 158,636.

My invention relates to electric arc lamps of a portable character, the primary object being to provide a light, compact and convenient hand lamp which is peculiarly adapted to therapeutic and surgical work, as well as for use in making blue-prints, photo-prints and so forth, and also as an auxiliary light for photographic work generally.

My lamp is entirely hand manipulated, requiring but one hand for the purpose, and does away absolutely with the use of the solenoid and its attendant connections and equipment for establishing and closing the arc, and may be operated through a flexible connection with any wall circuit or socket.

In the accompanying drawings, Fig. 1 is a side view of my device; Fig. 2 is an edge view; Fig. 3 is a vertical section on line 3—3 Fig. 2, showing the device in inoperative position; Fig. 4 is a section similar to Fig. 3, but somewhat fragmentary and on a larger scale, and showing the device in operative position; Fig. 5 is a section similar to Fig. 4, but more fragmentary and showing more in detail some of the principal features of the operating mechanism; Fig. 6 is a horizontal section on line 6—6 Fig. 5; Fig. 7 is a horizontal section on line 7—7 Fig. 4; Fig. 8 is a perspective view of the clutch; Fig. 9 is a perspective view of the lever 30; Fig. 10 is an edge view of a trigger switch.

Rigidly secured to the rear side wall of the casing 1, is the outstanding lug or post 2 provided at its inner end with a threaded portion for the reception of the nut 3. Swingingly mounted upon post 2, and secured by the nut 3, is the lever 4, provided at its free end with the slot 5. See Fig. 6.

Also mounted upon the post 2 is the helical spring 6, having its free end secured to the lever 4 by means of screw 7.

Slidably mounted upon the upright posts 8 and 8' within the casing, is the carbon holder 9 provided with a central opening 10 in which is secured the lower carbon 11 by the screw 12.

Carried on the rear face of the carbon holder 9 is the extension 13 (Fig. 6) which is embraced by the slot 5 in the lever 4.

Slidably mounted, intermediate its ends, upon the post 8' is the clutch yoke 14 and having one end adjustably but rigidly secured between the nuts 15 carried by the reciprocating clutch rod 16, and provided at

its opposite end with an opening 17 for the reception of the lower carbon 11. The clutch yoke 14 carries, adjacent the clutch rod 16, the oppositely disposed upstanding lugs or brackets 18 to which is swingingly secured the clutch member 19 by means of the cotter pin 20, and which is provided with the central opening 21 for the reception of the lower carbon 11. The free or outer end of the clutch member 19 is of finger-like extension 22, and carries upon its upper face the upstanding pin 23.

Secured to the front wall of the casing 1 are the spaced lugs or brackets 24, in which is slidably mounted the stem 25, carrying the collar 26 rigidly attached. A coil spring 27 is mounted upon the stem 25 between the collar 26 and the lower bracket 24. Figures 4 and 7.

Rigidly secured to the rear side wall of the casing 1 is another outstanding lug or post 28 (Figs. 4 and 6) upon which is swingingly mounted the lever 29 provided, intermediate its ends, with the notch 30 and at its free or swinging end with the slot 31. A head-block 32 is adjustably mounted upon the clutch rod 16 by means of the screw 33, and carries on its inner face the pin or reduced extension 34 (Fig. 6) which is embraced by the slot 31 in the lever 29. Also mounted upon the clutch rod 16, between the head-block 32 and the bottom of the casing, is the coil spring 35.

Rigidly secured to the bottom of the casing 1 is the upstanding lug or bracket 36 upon which is swingingly mounted the short arm 37 (Fig. 4) of the bell-crank lever 38 and carrying the pin 39. (Fig. 6.) The long arm 40 of the bell-crank lever 38 is loosely connected at its lower end with the upper end of the link 41, while the lower end of the link is loosely connected with the outer end 95 of the trigger 42 of the trigger switch 43.

Secured to the bell-crank 38, at its angle, is the upstanding finger 44, the upper end of which is connected by the coil spring 45 to the screw 46 in the top of the casing. Fig. 3. 100

Secured to the bottom of the casing 1 is the tube or receptacle 47, within which is mounted the trigger or toggle-joint switch 43, and which also serves as a handle for the device. 105

Resting upon supports 48, and securely fastened to the top of the casing, by means of the bolts 49, is the arc chamber 50 of sub-

stantially globular shape, with the opening 51, and carrying a tubular extension 52. Mounted within this tubular extension is the carbon holder 53 provided with a central 5 opening in which the upper carbon 54 is secured by the screw 55. The upper end of the tube is closed by the cap piece 56.

In wiring the device, one line, 56^a, of the circuit passes up through the tube 47 and 10 connects with the carbon holder 9 within the casing 1 and in which the lower carbon 11 is held. The other line, 57, is tied to the binding post 58 of the switch 43 and, when the switch 15 is closed as shown in Figures 4 and 10, the current travels up through plate 59, across the bar 60 and down the plate 61 to the binding post 62 to which the extension of line 57 is tied. From there this line passes up 20 through the casing 1, through the tube 63 and into the tubular extension 52 on the top of the arc chamber 50 where it connects with the carbon holder 53 in which the upper carbon 54 is held, thus completing the circuit.

The operation of my lamp, briefly stated, 25 is as follows: Assuming that the device is in inoperative position (Fig. 3), take it in either hand and press the button 64 on the long arm 40 of the bell-crank lever 38. This will straighten the toggle-link connection between 30 the arm 40 and the link 41, thus forcing the outer end of the switch trigger 42 downwardly and closing the switch. (Figures 4 and 10.) The closing of the circuit will be indicated by a snapping of the switch, 35 and it should be held in this position for a few seconds, permitting the current to flow until the carbons become heated. Then press the button further until the catch or dog 65, under pressure of spring 66, engages the pin 40 67 in the arm 40, which will hold it in operative position. As the short arm 37 of the bell-crank 38 is thus rocked downwardly, the pin 39 will engage the lever 29 in the 45 notch 30, thus rocking the free end of the lever downwardly, which will force the clutch rod 16 downwardly and with it the clutch yoke 14 and the clutch member 19. This will bring the finger extension 22 of the clutch member into contact with the upper 50 end of the stem 25 which will force the clutch member to an oblique position with the carbon 11, causing it to grip the carbon and force it downwardly, thus establishing the arc.

55 When it is desired to close the arc, release the catch 65 from the pin 67, when the spring 45 will rock the bell-crank lever 38 upwardly, thus releasing the pressure of the pin 39 upon the lever 29, when the spring 35 on the clutch 60 rod 16 will force the clutch member 19 upwardly, bringing the pin 23 on the clutch member into contact with the base of the arc chamber, thus releasing its grip on the carbon 11, after which the carbon holder 9 65 will be lifted by the tension of the spring 6

rocking the lever 4 upwardly and bringing the lower carbon into contact with the upper carbon, thus closing the arc.

It will be understood that the operating mechanism is so adjusted as to close the circuit, thus permitting the current to flow, through the carbons before they are separated and the arc established; and also to open the circuit before the arc is closed.

It will also be understood that the mechanism is provided with all necessary insulation to prevent leakage of the current.

I claim:

1. In an electric arc lamp, a casing having a pair of spaced upright posts therein, a carbon holder slidably mounted upon said posts, an upright reciprocating clutch rod mounted in said casing, a head-block secured to said clutch rod, a clutch yoke slidably mounted upon one of said posts and having one end secured to said clutch rod, a clutch member swingingly mounted upon said yoke, means for causing said clutch member to engage and release the carbon, a spring-controlled lever swingingly mounted in said casing and having its free end loosely connected with said carbon holder, another lever swingingly mounted in said casing and having its free end loosely connected with said head-block, means for operating said levers, an arc chamber carrying an extension, and a carbon holder mounted in said extension.

2. In an electric arc lamp, a casing having a pair of upright posts mounted therein, a carbon holder slidably mounted upon said posts, an upright reciprocating clutch rod, a head-block secured to said clutch rod, a clutch yoke slidably mounted upon one of said posts and having one end secured to said clutch rod, a clutch member swingingly mounted upon said yoke, means for causing said clutch member to engage and release the carbon, a spring-controlled lever swingingly mounted in said casing and having its free end loosely connected with said carbon holder, another lever swingingly mounted in said casing and having its free end loosely connected with said head-block, a bell-crank lever swingingly mounted in said casing, a spring-controlled finger member carried by said lever, a hollow tube secured to the bottom of said casing and having a switch mounted therein, said switch being provided with a trigger member, a link loosely interposed between the free end of said bell-crank lever and said trigger member, an arc chamber carrying an extension, and a carbon holder mounted in said extension.

3. In an electric arc lamp, a casing having a pair of upright posts mounted therein, a carbon holder slidably mounted upon said posts, an upright reciprocating clutch-rod, a head-block secured to said clutch rod, a clutch yoke slidably mounted upon one of said posts and having one end secured to said

clutch rod, a clutch member swingingly mounted upon said yoke, means for causing said clutch member to engage and release the carbon, a spring-controlled lever swingingly mounted in said casing and having its free end loosely connected with said carbon holder, another lever swingingly mounted in said casing and having its free end loosely connected with said head-block, a bell-crank lever swingingly mounted in said casing, a pawl to hold said bell-crank lever in operative position, a spring-controlled finger member carried by

5 said bell-crank lever, a hollow tube secured to the bottom of said casing and having a switch mounted therein, said switch being provided with a trigger member, a link loosely interposed between the free end of said bell-crank lever and said trigger member, an arc chamber carrying an extension, and a carbon holder mounted in said extension. 15

10 In testimony whereof, I have hereunto affixed my signature.
